UNITED STATES PATENT OFFICE.

JOSEPH L. WALKER, OF BATON ROUGE, LOUISIANA.

LADDER.

Application filed November 20, 1925. Serial No. 70,267.

This invention relates to a ladder of the extensible type, one of the objects being to provide a structure of this character the parts of which are connected together at all times but can be readily shifted relative to each other so that the ladder can be used as an ordinary straight ladder or as a step-ladder.

A further object is to provide means on the ladder sections which cooperate to automatically lock the sections against relative movement after they have been brought into line.

Another object is to provide a ladder which is durable and compact in construction and which can be folded or extended.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings, Figure 1 is a front elevation of the ladder extended.

Figure 2 is an enlarged transverse section through the ladder when completely collapsed or folded.

Figure 3 is an enlarged vertical section through the meeting portions of two sections of the ladder showing how they interlock when the ladder is in extended position, the position of one of the sections prior to the interlocking action, being indicated by broken lines.

Figure 4 is a section on line 4—4 Figure 3.

Figure 5 is a side elevation showing the ladder set up for use as a step ladder.

Referring to the figures by characters of reference 1 designates the bottom section of the ladder provided with side strips 2 the lower portions of which can diverge downwardly as shown. These strips are connected by rungs 3 which are preferably angular in cross section so that, when the ladder is set up for use, flat top faces 4 will be presented to the feet of the user. Secured along the outer sides of the strips 2 are combined reinforcing strips and hand rails 5 which serve to cover the ends of the strips and to

stiffen the side strips against lateral strains. The upper ends of the side strips 2 are convex from front to back and are provided with wear strips 6 the ends of which are bent downwardly as indicated at 7 and secured to the front and back faces respectively of the side strips. These strips 6 not only constitute wear devices but also serve to hold the top step 3 securely to the side strips.

Studs 8 are secured to the side strips 2 near the upper ends thereof at points between the two upper steps 3 and project into slots 9 extending longitudinally within the lower end portions of the side strips 10 of the second section 11 of the ladder. This second or intermediate section has the lower ends of its side rails 10 convex from front to back as shown at 12 and eccentrically disposed so as to constitute lifting cams.

A wear strip 13 extends along the lower end of each of these side strips 10 and has its end portions extended upwardly as shown at 14 and secured to the front and back faces of the strips 10. The front upwardly extended portion 15 is offset inwardly as at 16 to provide a recess for the reception of the second step 3 from the top of the lower section 1 when the ladder sections are assembled. Combined hand rails and reinforcing strips 17 are provided along the outer sides of the side strips 10 and serve to stiffen the section 11 against lateral strain and also to cover the ends of the steps 18 carried by said section.

The top section 19 of the ladder includes side strips 20 connected by rungs or steps 21 similar to those heretofore described and has the lower ends of its side rails cam-shaped as shown at 22 in Figure 5, this shape corresponding with the shape of the lower ends of the side rails or strips of the middle section 11. Slots 23 are also provided in the side strips or rails of the top section 19 and receive studs 24 extending from the side strips 10. This construction is similar to that illustrated in Figure 3. Reinforcing strips or hand rails 25 are secured to the side strips 20.

When it is desired to set up this ladder for use as a straight ladder the section 11 is swung upwardly relative to the bottom section 1 and the cam-shaped lower ends thereof will ride upon the adjacent step 3 of the section 1 as shown by broken lines 110 in Figure 3. This action will continue until the middle section 11 is brought into

- line with the section 1 at which time the ends of the cams 12 will pass over the engaged step 3 and the section 11 will drop with said step seated within the recesses 16. 6 This dropping of the section 11 is permitted in view of the stud and slot connections between the two sections. With the parts thus positioned the side strips 10 of the middle section 11 will thrust forwardly 10 against the upper steps of the bottom section.

The upper section 19 can then be similarly assembled with the middle section 11, it being understood that when this upper 15 section arrives in line with the middle section it will drop downwardly relative thereto and become interlocked with the two upper steps of the middle section in the same manner that the middle section is interlocked 20 with the two upper steps of the lower section.

When it is desired to collapse the ladder the sections are pulled upwardly relative to each other so as to lift the recessed portions 25 of the side strips out of engagement with the steps 3 engaged thereby. Thereafter the sections can be folded one into the other as shown, for example, in Figure 2. If preferred, however, the sections can be given 30 a triangular arrangement as illustrated in Figure 5, the intermediate section being utilized as a rear support for the front sec-

tion 1 while the top section 19 is utilized as a cross connection or brace, the same being connected by any suitable means to 35 one of the steps 3 of the section 1.

The slotted end of each side strip 10 of the middle section can be reinforced by a strip 17.

What is claimed is:

An extensible ladder including a section comprising side strips, rungs connecting the side strips, and pivot devices extending from the side strips between two of the rungs, another section including side strips having 45 slots extending longitudinally thereof adjacent one end into which said pivot devices extend, said side strips being each provided with spaced inclined faces on one edge for simultaneous wedging engagement with 50 two of the rungs of the first named section when the slotted side strips are shifting longitudinally in one direction, the slots being disposed between the inclined faces, and a stop shoulder at one end of each inclined 55 face for engagement with the adjacent rung, thereby to limit the wedging action of the inclined face during the relative movement of the sections.

In testimony that I claim the foregoing 60 as my own, I have hereto affixed my signature.

JOSEPH L. WALKER.
